US0D1067187S

(12) **United States Design Patent** (10) Patent No.: **US D1,067,187 S**
(45) Date of Patent: ** Mar. 18, 2025

(54) **BATTERY CLAMP**(71) Applicant: **The Noco Company**, Glenwillow, OH (US)(72) Inventors: **Jonathan Lewis Nook**, Gates Mills, OH (US); **William Knight Nook**, Shaker Heights, OH (US); **James Richard Stanfield**, Glendale, AZ (US); **Derek Michael Underhill**, Tempe, AZ (US)(73) Assignee: **The Noco Company**, Glenwillow, OH (US)(***) Term: **15 Years**(21) Appl. No.: **29/864,150**(22) Filed: **May 11, 2022****Related U.S. Application Data**

(63) Continuation of application No. 29/665,718, filed on Oct. 5, 2018, now Pat. No. Des. 967,025.

(51) **LOC (15) Cl.** ..... **13-03**(52) **U.S. Cl.**USPC ..... **D13/120**(58) **Field of Classification Search**USPC D13/118, 119, 120
CPC H01R 11/24

See application file for complete search history.

CLAIM

The ornamental design for a battery clamp, as shown and described.

DESCRIPTION

FIG. 1 is a front perspective view of an inner part of a new design for a battery clamp;

FIG. 2 is a left side elevational view thereof;
FIG. 3 is a right side elevational view thereof;
FIG. 4 is a front elevational view thereof;
FIG. 5 is a rear elevational view thereof;
FIG. 6 is a top plan view thereof;
FIG. 7 is a bottom plan view thereof;
FIG. 8 is a front perspective view of the inner part of FIG. 1, fitted with an exterior part of the assembled battery clamp;
FIG. 9 is a left side elevational view thereof;
FIG. 10 is a right side elevational view thereof;
FIG. 11 is a front elevational view thereof;
FIG. 12 is a rear elevational view thereof;
FIG. 13 is a top plan view thereof;
FIG. 14 is a bottom plan view thereof;
FIG. 15 is a perspective view of the inner part of the battery clamp shown in FIG. 1, a cable, and a nut for connecting the battery clamp and cable together;
FIG. 16 is another perspective view of the inner part of the battery clamp shown in FIG. 1, a cable, and a nut for connecting the battery clamp and cable together; and,
FIG. 17 is a perspective view of the inner part of the battery clamp shown in FIG. 1, a cable, and a nut for connecting the battery clamp and cable together.
The broken lines shown represent portions of the battery clamp that form no part of the claimed design.
